UNITED STATES PATENT OFFICE.

ROBERT W. WHITEHURST, OF NORFOLK, VIRGINIA, ASSIGNOR TO THE R. W. WHITEHURST COMPANY, OF SAME PLACE.

DESIGN FOR A LAND-ROLLER.

SPECIFICATION forming part of Design No. 34,107, dated February 19, 1901.

Application filed January 18, 1901. Serial No. 43,811. Term of patent 14 years.

To all whom it may concern:

Be it known that I, ROBERT W. WHITEHURST, a citizen of the United States, residing at Norfolk, in the county of Norfolk and State of Virginia, have invented and produced a new and original Design for a Land-Roller, of which the following is a specification.

Reference is to be had to the accompanying drawings, illustrating the design, in which—

Figure 1 is a side elevation of the land-roller. Fig. 2 is a face view of the same.

The design consists in the shape and configuration of the cylindrical land-roller illustrated in the accompanying drawings, in which each end of the cylinder is provided with radial spokes *a*, which have solid or unbroken surfaces in the same plane with the ends of the rim *b*, and each end of the cylin-

der is also provided with a plurality of pointed swells *c*, each of which is midway between every two spokes and which form with said spokes heart-shaped openings *d* in each end of the roller, and the face of said cylindrical roller is broad and smooth, as shown.

The roller shown and described is intended to be used in rolling lawns, roads, and similar places.

I claim—

The design for a land-roller herein shown and described.

In testimony whereof I affix my signature in the presence of two witnesses.

ROBERT W. WHITEHURST.

Witnesses:

E. B. WILSON,
JAMES A. SCOTT.
